(57) **CLAIM**

The ornamental design for a tool case, as shown and described.

DESCRIPTION

FIG. 1 is a front, right and top perspective view of a tool case showing our new design;

FIG. 2 is a rear, right and bottom perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof; and,

FIG. 9 is a front, right and top perspective view of the tool case in accordance with our new design illustrating a state in which the lid of the tool case is open.

The oblique line shading in the drawings shows translucent or transparent material. The lid of the tool case is entirely made of translucent or transparent material. The broken lines in the drawings illustrate the portions of the tool case which form no part of the claimed design.
